UNITED STATES PATENT OFFICE

WILLIAM T. WELCH, OF NEW ORLEANS, LOUISIANA

TOY AIRPLANE

Application filed October 28, 1929. Serial No. 403,049.

The present invention relates to improvements in toy airplanes and has for an object to provide an improved toy airplane of that type which is adapted to travel back and forward on a string, one end of which is secured to the wall or a fixed support and the other end held in the hand of the operator.

Another object of the invention is to provide an improved toy airplane so constructed as to assume a position of delicate balance and stability on the string with means to avoid the bobbing up and down of the airplane which action would interfere with the speed of the same.

15 A further object of the invention resides in providing an improved toy airplane in which an improved wing structure is had providing therefrom the supports for the landing wheels, suspension pulley and string 20 guide.

25 A still further object of the invention is to provide an improved airplane in which a modification of the rudder construction is involved to form a stabilizing eye for engaging the supporting string.

With the foregoing and other objects in view, the invention will be more fully described hereinafter, and will be more particularly pointed out in the claims appended 30 hereto.

In the drawings, wherein like symbols refer to like or corresponding parts throughout the several views—

Figure 1 is a perspective view of an improved toy airplane constructed in accordance with the present invention.

Figure 2 is a top plan view of the same.

Figure 3 is a side elevation.

Figure 4 is a front view.

40 Figure 5 is a side view with parts broken away and parts shown in section, and

Figure 6 is a transverse sectional view of the improved airplane.

Referring more particularly to the drawings, 10 designates a body or core in the nature of a fuselage. This body may be of any suitable material and has at its forward nose 11 a rotary propeller 12.

The rear portion of the body 10 carries 50 the rudder mechanism 13 which is prefer-

ably made from sheet metal. An eye 14 is also preferably stamped from the sheet metal of the rudder mechanism and twisted at substantially right angles as designated at 15 whereby the axis of the eye will lie 55 parallel with the axis of the body of the airplane to receive freely therethrough the supporting string 16, one end of which may be affixed to a wall or some other stationary support, while the opposite free end is held in 60 the hand of the operator.

This string 16 also passes beneath a grooved pulley 17 located at the center of balance of the airplane and journaled on a shaft 18 mounted in upstanding bearing arms 65 19 that are preferably stamped from the upper metal plane or wing 20. Cut out portions 21 are shown to be the result of the stamping out of the upstanding supporting arms 19, these arms being bent upwardly from the 70 plane of the wing 20. A string guide 22 is also stamped out from the material of the wing 20 as shown by the cut out portions 23 which overlies the body 10, so that the body reinforces and strengthens the wing structure 75 at a point where this cut out portion 23 occurs.

The string guide 22 is formed with an elongated slot 24 for receiving therethrough the string 16. The guide 22 is preferably 80 curved to conform somewhat to the curvature of the grooved periphery of the pulley 17 but is spaced from said pulley and acts to prevent the string from leaving the groove of the pulley and from getting between the sides of the 85 pulley and the supporting arms 19 where such string would jam and become difficult of disentanglement.

The lower plane is shown at 25 and is preferably formed in one piece with the upper plane 20, being connected therewith by a central web 26 which is formed with an opening 27 to receive the body 10 of the airplane, there being ample portions of the web 26 surrounding the body 10 to reinforce and 90 strengthen both wings. Also there are preferably struts or braces 28 between the upper and lower wings 20 and 25 outwardly of the web 26 to serve to maintain the proper relationship and distance between the two planes. 95 100

The lower plane contributes the structure for the landing gear. The supports 29 for the landing wheels 20 are stamped out of the metal of the lower plane 25, cut out portions 31 being left. As shown in Figure 6 the two supports 29 are cut out along their side and outer ends and bent down mutually in opposite directions toward one another to form the parallel spaced supporting legs for receiving therethrough the axle 32 of the landing wheels 30 and providing the strong arcuate or arched connecting structure 33 uniting the legs 29 with the lower wing structure.

In the use of the device, a string is secured at one end to a support and the airplane is threaded on the string as shown in Figures 1, 3 and 5, with the string passing through the tail eye 14, beneath and in the groove of the pulley 17 and through the slot 24 in the string guide 22. By lowering the free end of the string below that end attached to the support, the airplane will run along the string from the support toward the operator; then, by lifting the free end of the string to a point higher than the fixed end of the string, the airplane will be caused by gravity to descend along the string toward the support.

Due to the fact that the pulley 17, which sustains the loads, is located at the center of balance of the plane, a condition of stable equilibrium will be had, thus preserving the correct balance and upright position of the plane and having a tendency to always restore the plane to this condition whenever any extraneous force moves the same out of such condition. The action of the string 16 in passing through the eye 14 at the rudder construction or tail of the airplane will prevent that bobbing up and down of the plane which would otherwise occur and reduce the speed of the airplane on the string.

It is obvious that various changes and modifications may be made in the details of construction and design of the above specifically described embodiment of this invention without departing from the spirit thereof, such changes and modifications being restricted only by the scope of the following claims.

What is claimed is:

1. An improved toy airplane comprising a body, a metallic tail portion carried at the rear of the body, upper and lower metallic planes stamped from the same sheet of metal arranged above and below said body and having a perforated connecting web therebetween received about said body, braces between the outer end portions of said planes, rigid short pulley supports at the rear central portion of the upper frame, a pulley in said supports for receiving a supporting string, a slotted string guide struck out and bent upwardly from the upper plane adjacent said pulley, an eye stamped and twisted from

the metallic tail portion of the plane for also receiving said string, landing gear supports struck out and bent downwardly from the lower plane and having an arcuate upper structure integral with the lower plane, and landing wheels mounted in said landing gear support.

2. An improved toy airplane comprising upper and lower metallic planes having an integral web extending between the forward edges thereof at the central part of the airplane, said web having an opening therethrough, a cigar-shaped body extending between the planes and through the opening in said web, a propeller mounted in the forward portion of said body, a rudder structure mounted at the rear portion of the body and having an eye extending upwardly therefrom to receive a string, rigid short pulley supports struck out and bent upwardly from the rear central edge portion of the upper plane, a pulley rotatably mounted in said supports and adapted to receive the string therebeneath, a string guide on the upper plane just forward of the pulley, legs struck out from the central portion of the lower plane and bent downwardly therefrom, and landing wheels carried by said legs.

In testimony whereof I affix my signature.

WILLIAM T. WELCH.
